Angus Campbell

UNITED STATES PATENT OFFICE.

ANGUS CAMPBELL, OF JERSEY CITY, NEW JERSEY.

APPARATUS FOR WORKING ANCHORS.

Specification of Letters Patent No. 28,965, dated July 3, 1860.

To all whom it may concern:

Be it known that I, ANGUS CAMPBELL, of Jersey City, in the county of Hudson and State of New Jersey, have invented and 5 made certain new and useful Improvements in Means for Dropping Anchors; and I do hereby declare that the following is a full, clear, and exact description of the construction and operation of the same, reference 10 being had to the accompanying drawing, making part of this specification, wherein—

Figure 1, is a plan of a portion of the bulwarks with my apparatus fitted in place. Fig. 2, is a side elevation of the same; Fig. 15 3, is an elevation of the stopper on the cat head, Fig. 4, is a view of the tripping apparatus, and Fig. 5, is a cross section of the same.

Similar marks of reference indicate the 20 same parts.

The nature of my said invention consists in a rolling block placed on the bulwarks provided with a vertical hinged plate which protects the edge of the bulwarks from the 25 flukes of the anchor when dropped, and also acts to aid in hoisting the anchor by preventing the flukes becoming caught as they are raised above the bulwarks and rest upon the rolling block; I also make use of a 30 peculiarly fitted chain which holds the anchor firmly to place, but is self acting when the anchor is dropped and liberates the same as it is cast off; I also arrange my cat head stopper in such a manner relatively 35 with the rolling block that the act of casting the anchor off said block, also liberates the ring and chain from the cat head and the anchor falls down bodily. In previous instances where apparatus has been used for 40 casting the anchor flukes from off the edge of the bulwarks, the anchor was liable to swing and lurch at the risk of injuring the vessel; I provide a shank painter chain that is so fitted that the anchor can be lowered 45 gradually.

In the drawing *a*, represents a portion of the bulwarks or rail, and *b*, is the cat head. *c*, is a metallic plate setting on the rail *a*, and carrying between its vertical flanges the 50 rolling block *d*.

e, is a lever by which this block can be moved or secured in place by the staple and pin 1, projecting from said lever.

2, is a friction clamping screw taking 55 against one end of the block *d*, by which it

may be allowed to move more or less suddenly.

f is a plate hinged to *d*, at 3, and hanging vertically and within the flanges of the plate *c*, when the block *d*, is secured in place as in Fig. 5, but when said block is rolled, to cast off the anchor this plate *f*, passes outside the edge of the bulwarks to prevent the anchor injuring the vessel or becoming caught on the edge of the bulwarks; and when the anchor is being hauled up so as to rest on the block *d*, as seen in Figs. 1, and 2, this plate protects the bulwarks and forms a smooth surface for the fluke to slide over. To afford additional security and prevent the anchor slipping off the block *d*, I provide the chain *g* that is attached at 4, to the block *d*, and provided with a ring at the other end passing up onto a pendent pin 5, from the bulwarks. 75

The anchor being hoisted into place while the block *d* is turned down the chain *g* hangs loose and is passed over the anchor and the ring drawn onto the pin 5, and the turning of the block *d* back to place tightens 80 this chain, securely holding the anchor; but so soon as the reverse movement takes place, the chain is slackened and slips off the pin 5, and the anchor is free to fall. The speed of this movement in dropping the anchor 85 can be regulated by the clamping or friction screw 2.

The ring of the anchor *h*, is sustained by the chain *i*, to the cat head *b*, and *k*, is a stopper on said cat head taking the anchor 90 ring chain *i*. This stopper *k*, is formed with a slide 6, having an inclined end taking the T shaped head 7 of the chain *i*, or said inclined end might enter an elongated link. At the end of the slide 6, a pin 8, is inserted, 95 which while in place effectually prevents the anchor being dropped.

9, is a lever in the stopper *k*, the upper part of which takes the slide 6, and the lower end a chain *l*, that passes through 100 sheaves 10, 11, 12, and terminates by an attachment to the block *d*, (see Fig. 5.) When the rolling block *d*, retains the anchor this chain *l*, is tight but when the anchor is cast off this chain is loosened hence if the 105 pin 8, is withdrawn the end piece 7 of the chain *i*, will in consequence of the weight and the inclined shape, force back the slide 6, and the cat head chain *i*, will draw out of the ring as the anchor drops bodily into 110

the water without any manual labor applied to the anchor itself. If however it is intended simply to cast the anchor off the bulwarks and let it hang I allow the pin 8 to remain in place so that the cat head stopper may be effectual, and I pass the chain *m*, around the shank of the anchor and hook it over the pin 13, so that when the anchor is cast over the shank is in the bight 10 of the chain. This chain is fitted so as to be paid out by the chain wheel *n*, that is within the block *d*, and is turned gradually by the worm *o*, and handle *p*, which worm acts on a wheel *r*, on the same shaft 15 (*s*) as the chain wheel *n*, by this means the anchor can be lowered gradually until it hangs vertically under the cat head, (see Figs. 4 and 5).

Having thus described my said invention 20 what I claim and desire to secure by Letters Patent is—

1. The plate *f*, hinged to the rolling block *d*, for the purposes and as specified.

2. The chain *g* attached at one end to the rolling block *d*, and at the other end taking 25 the pin 5, for holding the anchor in place or disconnecting, by the self acting movement, in casting anchor as set forth.

3. The slide 6, and T shaped end 7 to the chain *i*, for liberating the ring of the anchor 30 when the slide 6, is allowed to move as set forth.

4. The combination of the stopper *k*, and rolling block *d*, by means of the chain *l*, whereby both ends of the anchor can be 35 simultaneously liberated, as described and shown.

5. The chain *m*, and wheel *n*, in combination with the rolling block *d*, and acting in the manner and for the purposes set forth. 40

In witness whereof I have hereunto set my signature this second day of June 1860.

ANGUS CAMPBELL.
